A. E. BERDON, C. RINGWALD AND A. B. GOMORY,
DISTRIBUTER HEAD FOR IGNITION DEVICES,
APPLICATION FILED MAY 25, 1917.

1,351,714.

Patented Aug. 31, 1920.

UNITED STATES PATENT OFFICE.

ALBERT E. BERDON, OF ANDERSON, INDIANA, AND CLARENCE RINGWALD AND ALBERT B. GOMORY, OF DETROIT, MICHIGAN, ASSIGNEES TO REMY ELECTRIC COMPANY, OF ANDERSON, INDIANA, A CORPORATION OF INDIANA.

DISTRIBUTER-HEAD FOR IGNITION DEVICES.

1,351,714.

Specification of Letters Patent. Patented Aug. 31, 1920.

Application filed May 25, 1917. Serial No. 170,820.

To all whom it may concern:

Be it known that we, ALBERT E. BERDON, CLARENCE RINGWALD, and ALBERT B. GOMORY, said BERDON residing at Anderson, in the county of Madison and State of Indiana, and said RINGWALD and GOMORY residing at Detroit, in the county of Wayne and State of Michigan, have invented certain new and useful Improvements in Distributer-Heads for Ignition Devices, of which the following is a full, clear, and exact description.

This invention relates to certain new and useful improvements in distributor heads for ignition apparatus and has for its object the provision of a distributor head which is particularly adapted for ignition devices used on multicylinder motors where there are a considerable number of high tension cables. The distributor head is particularly well adapted for use with V type engines wherein one-half the cylinders are arranged on one side and the other cylinders on the other side of a vertical plane. One of the objects of the present invention resides in the provision of a device which enables the cables forming the high tension leads to be readily attached to the distributor posts with a minimum of labor and material. Other objects reside in the provision of a head which is practically water-proof, thereby minimizing the liability of the short circuits. Other objects reside in the provision of a head in which the leads may be led to their proper distributor posts irrespective of the sequence of firing order and without unduly increasing the size of the apparatus.

In the drawings:

Figure 1 shows in perspective a distributor head with the cap and cables in place. Fig. 2 is a sectional view showing the interior construction, the section being taken on line 3—3 of Fig. 3 and with certain of cables detached for the sake of clearness.

Fig. 3 is a top plan view of a distributor with the high tension cables in place and the cap removed.

The body of distributor comprises a shell 10 having integral therewith and projecting therefrom at the top and at opposite sides thereof two extensions 11. The body is divided by a horizontal wall 12 into a lower chamber 13 and an upper chamber 14. The

lower chamber is the distributor chamber 55 and the upper chamber is the cable receiving chamber.

Embedded in the dividing wall 12 are L shaped distributor posts 15 and a central block 16 carrying supply contact button 17. 60 These parts together with a rotating distributor segment constitute the high tension current distributor.

Immediately above the L shaped posts 15 and extending upwardly from the upper 65 face of the partition wall 12 are bosses 18 which are co-axially drilled and tapped as shown at 19 to receive screws 20.

There is also a boss 18^a supporting the central contact block 16 which is also drilled and tapped as shown at 19 to receive a screw 20. This boss 18^a is disposed above the plane of bosses 18, and serves to divide the cable receiving chamber in such a manner that the cables can be placed therein in a very compact relation whereby to insure that the cables will not be moved relatively to the chamber with the jarring of the automobile in which the distributor is used. This construction will insure that the connections of 70 the cables with the posts will not easily be disturbed.

It will be understood that the L shaped distributor posts 15 are also tapped, whereby a good electrical connection is established 75 between the screws 20 and the posts 15.

In the present embodiment there are nine high tension leads, but it will be understood that the number of leads depends upon the number of cylinders to which current is to 90 be distributed. 21 is the supply lead and passes into chamber 14 at the side of the circular shell. 22, 23, 24, 25 constitute one group of leads and are admitted into chamber 14 through a number of parallel holes 95 in one of the extensions 11. 26, 27, 28 and 29 constitute another group of leads and extend into chamber 14 through similar parallel holes in the other extension 11. Before placing the above cables in position they 100 are pierced by an awl or similar tool. Then after they have been passed through the holes in the extensions 11 and the shell 10, these awl holes in the cables permit the screws 20 to be forced through the cables. 105 The screws are pointed at their lower ends as shown in Fig. 2 and these pointed ends are adapted to wedge through the insulating

covering on the cables and through the stranded wires 30 therein. The screws 20 clamp the respective cable ends tightly down upon the bosses 18 and at the same time establish a good electrical connection between the wires 30 within the cables and the respective distributor posts 15 or central contact block 16.

The screw devices provide an exceedingly simple method of attaching the cables to the current distributing devices and obviate the necessity of employing clips and terminal devices which would, on account of the crowded condition of the cables in chamber 14, tend to cause short circuits and jumping of the sparks to improper terminals. The chamber 14 being larger than chamber 13 provides ample room for "crossing" the cables as shown in Fig. 3. This crossing in the head is desirable in multi-cylinder engines due to the firing order in the different cylinders, and in order to lead the cables directly to their proper cylinders without twisting and crossing them outside the distributor head.

After the cables are properly attached a cap 32 is placed over the top of the chamber 14 and secured to the body of the head by screws 33. This cap completely incloses and seals the upper chamber thereby preventing the ingress of water and dirt.

The distributor head may be retained upon the ignition device in any desired manner, as by the clips 34 shown in dotted lines in Fig. 1.

It will be understood that the shell 10, the extensions 11 and the dividing wall 12 are preferably molded integrally from a plastic composition such as bakelite, condensite, or any of the well known phenolic condensation products. The cap may be and is preferably made from a similar material.

It will be understood that the invention may be modified in various ways which will occur to those skilled in the art. What we claim as our invention is particularly pointed out in the appended claims.

We claim:

1. A distributor head for ignition apparatus comprising a shell divided by a partition into a cable receiving chamber and into a distributor chamber; distributor posts provided in the partition and exposed to the distributor chamber; a plurality of insulated cables extending through the shell into the cable receiving chamber; means for detachably securing the ends of said cables in position within the cable receiving chamber and for connecting them severally to the posts; and a detachable cover for the cable receiving chamber for permitting ready access to the cable securing means, said cover being removable from the head without interference with any of said cables.

2. A distributor head for ignition apparatus comprising a shell divided by a partition into a cable receiving chamber and into a distributor chamber; distributor posts provided in the partition and exposed to the distributor chamber; a plurality of insulated cables extending through the shell into the cable receiving chamber, said cables having their ends flattened out and provided with holes passing through the insulated portion and the conducting portion of the cables; screws passing through said holes and having threaded engagement with the distributor posts whereby to hold said cable ends in position and for making electrical connection with the posts; and a detachable cover for the cable receiving chamber for permitting ready access to the cable securing means, said cover being removable from the head without interference with any of said cables.

3. A distributor head for ignition apparatus comprising a hollow body portion divided by a partition wall in order to provide a distributor chamber and a cable receiving chamber, a plurality of distributor posts disposed in circular relation in said partition wall, a plurality of bosses upon which cables may be disposed for mechanical attachment to the head and for electrical connection with the posts, provisions in the head affording means for the inserting of the ends of cables into the cable receiving chamber, means for effecting mechanical connection of the cables to the bosses and electrical connection with the posts, and a boss disposed centrally with respect to the first named bosses, and supporting a center contact, and adapted to receive a cable connected with the center contact, said center boss being disposed above the plane of the other bosses in order to provide means whereby the cables may be placed in compact relation within the cable receiving chamber.

4. A distributor head for ignition apparatus comprising a shell divided by a partition into a cable receiving chamber and into a distributor chamber; L-shaped distributor posts embedded in said partition, each having one leg thereof exposed in the distributor chamber; a plurality of insulated cables extending through the shell into the cable receiving chamber, said cables having their ends flattened out and provided with holes passing through the insulated portion and the conducting portion of the cables; screws passing through said holes and having threaded engagement with the distributor posts whereby to hold said cable ends in position and for making electrical connection with the posts; and a detachable cover for the cable receiving chamber for permitting ready access to the cable securing means, said cover being removable from the head without interference with any of said cables.

the head without interference with any of said cables.

5. A distributor head for ignition apparatus comprising a shell divided by a partition 5 into a cable receiving chamber and into a distributor chamber; a supply contact and a plurality of distributor posts disposed in said partition wall; cable attaching provisions carried by said partition; said body 10 being provided with oppositely disposed groups of apertures leading into the cable receiving chamber whereby spark plug cables may be brought into said cable receiving chamber and connected to proper 15 distributor posts, and may be brought out
- of said distributor head in correct order and connected without crossing with the various spark plugs; said body being provided with an aperture for the projection therethrough of a supply cable connected with said supply 20 contact; and a cover for the cable receiving chamber for protecting and concealing the crossed cables, said cover being removable without interference with any of said cables.

In testimony whereof we affix our signatures.
